COMBINATION SIGNAL LAMP AND SIREN FOR A JUVENILE VEHICLE

Viktor Schreckengost, Cleveland Heights, Ohio, assignor
to The Murray Ohio Manufacturing Co., Nashville,
Tenn., a corporation of Ohio

Filed Aug. 16, 1965, Ser. No. 86,591

Term of patent 14 years

(Cl. D48—24)

Fig. 1

Fig. 2

Fig. 3

Fig. 4

Fig. 5

FIGURE 1 is a side elevation view of a combination signal lamp and siren for a juvenile vehicle showing my new design;

FIGURE 2 is a rear elevation view thereof;

FIGURE 3 is a front elevation view thereof;

FIGURE 4 is a top plan view thereof; and

FIGURE 5 is a bottom plan view thereof.

I claim:

The ornamental design for a combination signal lamp and siren for a juvenile vehicle, substantially as shown and described.
